UNITED STATES PATENT OFFICE.

JAMES HASLAM, OF SIOUX FALLS, SOUTH DAKOTA.

TATTING-SHUTTLE.

1,287,010.

Specification of Letters Patent. Patented Dec. 10, 1918.

Application filed April 11, 1918. Serial No. 227,922.

To all whom it may concern:

Be it known that I, JAMES HASLAM, a citizen of the United States, residing at Sioux Falls, in the county of Minnehaha and State 5 of South Dakota, have invented certain new and useful Improvements in Tatting-Shuttles, of which the following is a specification.

This invention relates to certain new and useful improvements in a tatting shuttle and 10 it aims to provide a simply constructed shuttle embodying a rotatable bobbin with means for rotating the same to easily wind the thread thereon.

Further, the invention resides in an improved lock for releasably holding the bobbin against unwinding, which lock is releasable upon imparting a longitudinal movement to the bobbin by pulling on the thread lengthwise of the shuttle.

20 In the drawings

Figure 1 is a side elevation of the improved tatting shuttle;

Fig. 2 is a longitudinal section thereof on line 2—2 of Fig. 1; and

25 Fig. 3 is a cross sectional view on line 3—3 of Fig. 2.

In the preferred embodiment of the invention the barrel or body 1 of the shuttle is provided with a pointed nose or end 2 30 that may be integrally formed therewith although it is here shown as separable therefrom. The opposite end of the barrel is internally screw threaded to receive a combined locking and closure plug 3 which has 35 its inner end formed with an annular series of ratchet teeth 4 for interlockingly meshing with similar teeth 5 that are formed on the adjacent end of the bobbin or spool 6.

This bobbin is spool-shaped and is arranged 40 within the chamber of the barrel for longitudinal movement therein. The heads 7 serve as bearings for the spool both in its longitudinal and rotative movements, an additional bearing being provided by a 45 shaft 8 which is passed through an opening 9 in the ratchet nut or plug 3 and fixedly carries the bobbin. A coiled expansion spring 10 is seated in a well or recess 11, formed at the inner end of the bobbin chamber, and bears outwardly against the opposing 50 end of the bobbin to resiliently and yieldably hold the ratchet teeth of the bobbin in interlocking mesh with the teeth of the ratchet nut. The spring receives the

projecting end of the shaft 8 for being 55 steadied and guided thereby.

A depressible knob 12 is carried by the outer end of shaft 8, the same being guidingly received within a counterbore 13 in the nut 3. When it is desired to wind 60 thread on the bobbin the knob is turned in the direction in which the coöperating ratchet teeth will yieldingly pass or ride by each other, the bobbin being fixed on the shaft 8.

65 In practice, the thread is passed through a longitudinal slot 14 in the barrel 1 and is wound on the bobbin merely by revolving the handle knob, the spring maintaining a locking relation between the ratchet teeth so 70 that normally the bobbin is locked against unwinding rotation.

75 Unwinding motion may be imparted to the bobbin when the knob is depressed to disengage the intermeshing ratchet teeth from one another but this operation is not always convenient in tatting, therefore, the slot 14 is made sufficiently long, extending beyond the inner end of the bobbin, so that the thread may be pulled toward the pointed end 2, which exertion, by reason of the bobbin being held against rotation, will slide the bobbin and its teeth away from or out of engagement with the ratchet teeth of nut 3 and then revolve said bobbin and feed 85 out the thread until the tension on the latter is less than that of the spring when the ratchet teeth will be reengaged with each other. Therefore, all the user is required to do, in order to pay out additional thread, 90 is merely to pull the thread longitudinally of the shuttle body toward its nose, which releases the ratchet lock and permits free rotation of the bobbin.

95 The thread is easily wound onto the bobbin, and the unwinding is always under the control of the user. The shuttle body may be made of any light or desirable material which may be given a smooth and neat finish, and although the construction has 100 been specifically described and illustrated, changes may obviously be resorted to as fall within the scope claimed.

What is claimed is:

1. A tatting shuttle comprising a cylindrical barrel having one end pointed and its opposite end internally screw threaded, said barrel having a bobbin chamber and a longi-

tudinal slot through its side, a ratchet nut threaded in the opened end of the barrel and formed with an axial opening and a counterbore, the opposite end of the chamber being 5 formed with a well, a spring located in the well, a bobbin spool rotatably disposed in the chamber and provided on its outer end with ratchet teeth interlocking with the teeth of the ratchet nut, a shaft passing 10 through the opening of the latter and fixedly carrying the bobbin spool, and a knob carried by the outer end of the shaft and received by the counterbore of said nut.

2. In a tatting shuttle, a barrel having a 15 bobbin chamber formed with a longitudinal slot opening through its side, a bobbin rotatable and slidable in the chamber, means positively holding the bobbin against unwinding movement and releasable therefrom 20 by exerting a pull on the thread longitudinally of the shuttle, and manually operable means for rendering said first means inoperative to permit free rotation of the bobbin.

3. In a tatting shuttle, a barrel having a 25 bobbin chamber formed with a longitudinal slot opening through its side, a bobbin rotatable and slidable in the chamber, a ratchet means in one end portion of the barrel, and coöperating ratchet means on the bobbin 30 normally interlocking with the first ratchet means to prevent unwinding movement of the bobbin and releasable from said first ratchet means to permit unwinding movement of the bobbin on moving the bobbin longitudinally within the chamber, the slot 35 in said barrel extending below the thread

wound on the bobbin to permit the latter being moved longitudinally by pulling the thread in the same direction.

4. In a tatting shuttle, a barrel having a 40 bobbin chamber formed with a longitudinal slot opening through its side, a bobbin rotatable and slidable in the chamber, means permitting free winding movement of the bobbin and preventing unwinding movement 45 thereof, and manually operable means for moving the bobbin longitudinally in its chamber whereby the first means is rendered inoperative to permit free rotation of the 50 bobbin.

5. A tatting shuttle comprising a cylindrical barrel having one end pointed and its opposite end internally screw threaded, said barrel having a bobbin chamber and a longitudinal slot through its side, a closure member engaged in the opened end of the barrel and formed with a ratchet part on its inner end, the opposite end of the chamber being formed with a well, a spring located in the well, a bobbin spool rotatably disposed in the chamber and having its outer end formed with ratchet teeth for engaging the ratchet part of the closure member, and a shaft extending through the closure member to provide means for disengaging the 60 ratchet teeth.

In testimony whereof I affix my signature in the presence of two witnesses.

JAMES HASLAM.
